[57] CLAIM

The ornamental design for a combined container for candy or the like and toy building block, as shown.

DESCRIPTION

FIG. 1 is a front elevational view of a combined container for candy or the like and toy building block showing my new design;

FIG. 2 is a top plan view;

FIG. 3 is a bottom plan view;

FIG. 4 is an elevational view looking from the left of FIG. 1;

FIG. 5 is an elevational view looking from the right of FIG. 1;

FIG. 6 is a sectional view taken on the line 6—6 of FIG. 5 looking from the left;

FIG. 7 is a sectional view taken on the line 7—7 of FIG. 1 looking from the right;

FIG. 8 is an enlarged fragmentary sectional view taken on the line 8—8 of FIG. 4 looking down;

FIG. 9 is an enlarged fragmentary sectional view taken on the line 9—9 of FIG. 3 looking from the left.
